UNITED STATES PATENT OFFICE.

JAMES ALFRED PEARSALL AND CASSIUS MARSHALL WALKER, OF DENVER,
ASSIGNORS TO THE ROCKY MOUNTAIN DRILL COMPANY, OF PUEBLO,
COLORADO.

ROCK-DRILLING MACHINE.

SPECIFICATION forming part of Letters Patent No. 510,517, dated December 12, 1893.

Application filed November 25, 1891. Serial No. 413,152. (No model.)

To all whom it may concern:

Be it known that we, JAMES ALFRED PEARSALL and CASSIUS MARSHALL WALKER, citizens of the United States, residing at Denver, in the county of Arapahoe and State of Colorado, have invented certain Improvements in Rock-Drilling Machines, of which the following is a specification.

The object of our invention is to produce improved mechanism for operating drills which will prove to be durable and effective in operation; and which, striking a firm blow upon the head of the drill or drill-holder, will prevent the rebound of the drill.

Another object of our invention is to produce improved means in a drilling machine for keeping the space around a tool clean and free from dust.

In the accompanying drawings, Figure 1 is a side elevation of our machine. Fig. 2 is a central vertical longitudinal section of Fig. 1, showing some of the driving parts in elevation. Fig. 3 is a longitudinal section taken on the line 3, 3, of Fig. 2. Fig. 4 is a plan view of the hammer and guide-piece, detached. Fig. 5 is a side elevation of valves and stem. Fig. 6 is a similar view, taken at right angles to that shown in Fig. 5. Fig. 7 is a vertical cross section of the hammer and guide piece. Figs. 8 and 9 illustrate the relative positions of the two valves in one operation of the machine; and Figs. 10 and 11 illustrate the same in their other positions.

Referring to the figures on the drawings, 1 indicates the shell of our machine, which is preferably made of cast metal. It is adapted to be carried upon a suitable frame, as for example a tripod, and to be advanced by any suitable means in the direction of its cut.

2 indicates the head of the shell, in which is carried the main piston cylinder 3 and the valve piston cylinders 4 and 5. The valve-piston cylinders are connected by ports 6 and 7, and 8 and 9 respectively, which communicate with an intermediate valve seat 10, from which, at right angles, lead the ports 11 and 12, respectively communicating with it, opposite the ports 6 and 7 and 8 and 9. The valve-seat is preferably slightly tapered to receive a correspondingly tapered valve-stem 13 which

carries valves 14 and 15 adapted to control the ports 6, 7, and 11 and 8, 9, and 12 respectively. The lower end of the valve-stem sets upon a bench 16 in the shell, where a pointed screw 17 is provided as a bearing, and by which the stem may be moved toward the valve-seat to compensate for wear of the parts.

The valve 14 is preferably provided with ports 18 and 19, and a medial wall 20. The valve 15 is provided with a single recess or port 21. The valves are so arranged with respect to each other that by the partial rotation of the valve-stem they may control each set of cylinder ports, as shown in Figs. 8, 9, 10, and 11 respectively.

22 indicates a vent communicating with the interior of the cylinder 5.

23 indicates a supply pipe communicating with a source of steam or compressed air, not illustrated; and 24 indicates a branch supply-pipe communicating with the pipe 23, and with the cylinders 4 and 5 respectively through connections 25 and 26.

27 indicates one of the valve-pistons and 28 the other.

29 indicates a stem of the piston 27, and 30 that of the piston 28. These stems pass through bushings 31 and 32, respectively, and are pivotally connected, as by heads 33 and 34 respectively to pitmen 35 and 36, which are pivotally connected to dogs 37 and 38 respectively, which are carried upon a pivoted shaft 39 journaled in the side of the shell.

40 indicates trip-levers secured to the dog 38. These trip-levers extend in opposite directions, and are designed alternately to impinge against fingers 42 and 43, respectively secured, as by bosses 44 and 45, to the valve-stem 13. The office of these trip levers is to impart the required rotatory movement to the valves 14 and 15 to control the cylinder ports in the manner above suggested.

46 indicates a main piston.

47 indicates the main piston rod passing through a bushing 48 in the end of its cylinder, and carrying upon its end a hammer 49. To this hammer is securely fastened a guide-piece 50 adapted to reciprocate within longitudinal bearings in the shell.

51 indicates an aperture in the end of the

shell to permit the free movement of the guide-piece.

52 and 53 indicate ways in the sides of the hammer the latter having a beveled end 54.

5 55 indicates a drill holder adapted to carry a drill 56, and having a drift hole 57 to assist in removing the drill when required. The holder is yieldingly urged toward the hammer as by a spiral spring 58, seated at 10 one end in the end of the shell, and bearing at the other end against a collar 59 secured to the holder.

60 indicates an obliquely channeled collar, with which an oblique rib 61 from the guide-piece 50 is adapted to engage in each reciprocation of the guide-piece. By this arrangement the rib imparts a slight rotatory movement with each reciprocation of the guide-piece. Upon the next movement of the guide-piece, the rib engages with the next channel and imparts an additional rotatory movement. Each reciprocation of the hammer, therefore, sets the drill anew.

62 indicates a tubular cover communicating with a recessed carrier upon the outer end of a recessed housing 63 around the drill, and near its cutting end the diameter of the head of the drill should be somewhat greater than the tubular cover, so that the hole formed 25 by the drill will be larger than the cover, as indicated by dotted lines in Figs. 2 and 3.

64 indicates a branch pipe communicating with the supply pipe 23, and with the recess in the housing 63.

35 65 indicates an ordinary three-way cock, adapted to direct the supply from the pipe 23 into the pipe 24, or the pipe 64, at will.

In operation, suppose the valve-operating piston and the main piston to be in relative 40 positions, shown in Figs. 2 and 3, and steam to be admitted into the pipe 24. The valves 14 and 15 will then be in the relative positions shown in Figs. 8 and 9 respectively. Steam admitted into the cylinder 4 will pass through 45 the port 8 into the valve-seat 10, and thence through the port 12 into the cylinder 3. The piston 46 will then be driven toward the head of the cylinder carrying the hammer 49 with it. The point of the dog 37 will travel along 50 the way 53 until it reaches the beveled end 54, when it will be released. This will occur just as piston 46 reaches the limit of its travel.

Upon the release of the dog 37 the steam in the cylinder 5, above the piston 28, will drive the 55 piston-rod 30 a short distance, sufficient to operate the trip-lever 40 and force it against the finger 43; thereby rotating the valves 14 and 15 and reversing them to the relative positions shown in Figs. 10 and 11, respectively.

60 Thereupon live steam from the cylinder 4, through the ports 6 and 11, enters the cylinder 3 and drives the piston 46 in the opposite direction. The dead steam exhausts through the ports 12 and 9 into the cylinder 5 and out 65 through the aperture 22. It will be observed in this connection that in the movement of

the piston previously described, the exhausts pass through the ports 11 and 7 into the cylinder 5 and thence out through the opening 22. As the hammer driven by its piston 46 descends, it engages upon its ways 52 and 53 the dogs 37 and 38. The dog 37 is retained in its way, but the dog 38, slipping away from the hammer, is released, and the piston 27 is operated by the steam in the cylinder 4 to bring the trip-lever 41 against the finger 43, and restores the valves 14 and 15 to the positions shown in Figs. 8 and 9 respectively. Thereupon the operation is repeated as before.

The operations above described are performed with great rapidity, and with each complete reciprocation the tool-holder is given a sharp quick blow, and is followed by the hammer, under pressure of steam, long enough to prevent its rebound. The holder, therefore, presents a rigid resistance to the stroke of the hammer each time, and the tool is driven evenly and regularly. When a tool becomes clogged with cuttings the operation of the hammer may be interrupted and the steam or air forced through the pipe 64 into the cover 62. In this manner a blast of air is driven into the bottom of the hole and the débris is blown out around the cover.

While we have illustrated and described a particular form of embodiment of our invention, we do not wish to limit ourselves to the details of construction; but desire to modify and vary them at will within the scope of our invention.

What we claim is—

1. The combination with a cylinder and piston therein, and a pair of valve piston cylinders, of a valve adapted to admit the steam alternately above and below said piston from one of the valve piston cylinders and to permit its exhaust into the other, substantially as specified.

2. The combination with a cylinder and piston, and a valve, of a pair of valve piston cylinders and valve pistons therein adapted to control the movement of the valve to admit the steam from one of the valve piston cylinders alternately above and below the piston and permit the exhaust into the other, and mechanism operatively connecting the valve pistons with the valve, substantially as specified.

3. The combination with a main piston and cylinder, a controlling valve and a pair of valve piston cylinders and pistons, of mechanism operatively connecting the main piston with the valve pistons whereby the movement of the main piston through the valve pistons and connecting mechanism actuates the valve to admit the steam into the main cylinder behind the piston, substantially as specified.

4. The combination with a main cylinder and piston, and a valve, of a pair of valve piston cylinders and valve pistons, said valve pistons being adapted to control the valve, mechanism adapted to dog the valve pistons

and mechanism operatively connecting the dogging mechanism with the main piston whereby the movement of said main piston releases the dogging mechanism and permits 5 the valve pistons under steam pressure to actuate the valve, substantially as specified.

5. The combination with a shell, of a main cylinder, a controlling valve and a pair of cylinders all arranged longitudinally with respect to each other, said shell having ports communicating each end, respectively, of the main cylinder with the adjacent ends of the other cylinders, said valve being adapted to control the supply and exhaust to and from 15 the main cylinder through said ports, substantially as specified.

6. The combination with a shell and main piston, of a controlling valve separate cylinders, supply pipes connected thereto, pistons 20 in said cylinders, and a trip lever operatively connected to said pistons and adapted to actuate the valve, substantially in the manner and for the purpose specified.

7. The combination with a shell, piston, rod, 25 and hammer, of a valve for controlling the supply of steam to the piston, a trip-lever under constant pressure for operating the valve, and a dog controlled by the movement of the

hammer for actuating the trip-lever, substantially as set forth.

8. The combination with a shell, piston, rod, and hammer, of a valve adapted to control the supply of steam to the piston, pivoted dogs and trip levers, ways in the hammer controlling the dogs, and pistons adapted to actuate the dogs when released from the hammer to cause the trip levers to intermittently actuate the valve, substantially in the manner and for the purpose specified.

9. The combination with a shell and reciprocatory hammer, of a guide-piece and oblique rib, a tool-holder having an obliquely channeled collar adapted to engage with the oblique rib, substantially in the manner and for the purpose specified.

10. In a rock drill, the combination with a tool-holder and tool, of a tubular cover surrounding the tool, and mechanism for supplying a blast within the cover around the tool, substantially in the manner and for the purpose specified.
